PLEATED UMBRELLA

Edward Chodosh, 36-40 Northiam St.,
Hackney E. 8, England

Filed Oct. 8, 1964, Ser. No. 82,084

Claims priority, application Great Britain Apr. 10, 1964

Term of patent 14 years

(Cl. D88—3)

FIG. 1.

FIG. 4.

FIG. 2.

FIG. 3.

FIG. 5.

FIG. 6.

FIGURE 1 is a top perspective view of the pleated umbrella of my new design wherein the outer edges of the gores are repleated in a plurality of peripheral rows presenting a ruched effect when the umbrella is in closed position;

FIGURE 2 is a side perspective view of the umbrella shown in FIGURE 1, the umbrella being in closed position;

FIGURE 3 is a side perspective view of the opposite face of the closed umbrella shown in FIGURE 2;

FIGURE 4 is a top perspective view of another embodiment of the pleated umbrella of my design wherein the outer edge is plain and a single peripheral row is repleated a short distance from the edge so as to present a flounced effect when in closed position;

FIGURE 5 is a side perspective view of the umbrella shown in FIGURE 4, the umbrella being in closed position; and

FIGURE 6 is a side perspective view of the opposite face of the closed umbrella shown in FIGURE 5.

The ornamentation on the remaining plain gores of the umbrellas shown in FIGURES 1 and 4 are like that on the front center gore and in proper relation thereto.

An essential part of the design lies in the chevron effect where the radial and peripheral pleats cross.

I claim:

The ornamental design for a pleated umbrella, substantially as shown and described.
